UNITED STATES PATENT OFFICE.

FREDERICK WM. KLEIN, OF READING, PENNSYLVANIA, ASSIGNOR TO THE READING BRAID COMPANY, OF SAME PLACE.

DESIGN FOR BRAID.

SPECIFICATION forming part of Design No. 28,777, dated May 31, 1898.

Application filed March 5, 1898. Serial No. 672,783. Term of patent 14 years.

To all whom it may concern:

Be it known that I, FREDERICK WM. KLEIN, a citizen of the United States, residing at Reading, in the county of Berks and State of Pennsylvania, have invented and produced a new and original Design for Braid; and I do hereby declare the following to be a full, clear, and exact description of the same, reference being had to the accompanying drawings, forming a part thereof.

This is a new and original design for braid.

In the accompanying drawings, Figure 1 is a view illustrating a piece of braid made in accordance with my design. Fig. 2 is an end view.

Referring to the drawings, A designates a piece of braid having a body portion *a*, closely woven and provided at one edge with upper

and lower endless loops *b* *b'*, forming an open-work double edge B, said loops being formed by interlaced and interlocking threads, the essential feature of my design being the braid formed with an approximately flat body portion having an open-work double edge of approximately heart shape in cross-section, being so formed by upper and lower interlaced loops.

I claim as my invention—

The design for braid, substantially as herein shown and described. 30

In testimony whereof I affix my signature in presence of two witnesses.

FREDERICK WM. KLEIN.

Witnesses:

GEO. A. WANNER,
ED. A. KELLY.
